United States Patent Office.

ALCIBIADES J. WHITTIER, OF ROXBURY, MASSACHUSETTS.

Letters Patent No. 68,326, dated August 27, 1867.

IMPROVED MOSQUITO-BAR AND WINDOW-SCREEN.

The Schedule referred to in these Letters Patent and making part of the same.

TO ALL WHOM IT MAY CONCERN:

Be it known that I, ALCIBIADES J. WHITTIER, of Roxbury, in the county of Norfolk, and State of Massachusetts, have invented certain new and useful improvements in Mosquito-Bars or Window Screens, of which the following is a full, clear, and exact description, reference being had to the accompanying drawings, making part of this specification, in which—

Figure 1 is a front elevation of a window, with the lower sash raised, and one of my improved screens unrolled between the lower edge of the sash and the window-sill.

Figure 2 is a similar front elevation, with the screen rolled up, and the sash lowered.

Figure 3 is a transverse section of fig. 1.

Figure 4 is a transverse section of fig. 2.

Figure 5 is a horizontal plane section on the line A, B of fig. 1.

Figure 6 is a central longitudinal section of the self-winding roll detached, and which takes up the screen when the sash is lowered. The spring *f*, connected with the tube *e* and the shaft *E*, operates the roll in winding.

Figure 7 is a transverse section of the tube, shaft, and spring connected.

In this invention one end of the fabric of which the screen *A* is composed is fastened to a bar, *B*, which rests on the sill *C*, and is secured to the pulley-stiles *D* by sliding-bolts *a*, which are fastened to the bar *B*, and enter the stiles; and the other end of the screen *A* is fastened to the self-winding roll *F*, the central shaft *E* of which is held firmly in the plates *b*, shown in fig. 6, at each end of the roll. One end of the spring *f* is connected with the tube *e*, and the other end to the shaft *E* of the roll. The tube *e* and heads *c* revolve on the shaft *E*. A hook, *d*, applied to bar *g*, is turned by a thumb piece, *h*, to hook over a pin, *n*, in the rail of the sash, and connect the sash with the rolling-screen.

By releasing the hook *d*, and withdrawing the bolts *a*, the rolling-screen may be easily removed, and it may be as easily connected by placing the bar *B* on the sill *C*, and sliding the bolts into holes in the stiles *D*, and by turning the hook *d* to engage with the pin *n* in the sash. My improved roller-screen may be applied above the top sash in the same manner as below the lower sash. Raising the lower sash unrolls the screen, and the sash may be held up by any suitable window fastening. When the sash is lowered or closed the screen *A* winds on to the self-acting roll.

This improved self-rolling window-screen and mosquito-bar is intended to be used for the same purposes that other window-screens or mosquito-bars are used for. It is quite as well adapted to large windows as to small ones. It is easily connected or disconnected, and is portable, for transportation, sale, or use, or, when not in use, to pack in small space for safe keeping.

What I claim as new, and desire to secure by Letters Patent, is—

The hook *d* and the bolts *a*, or their equivalent, when applied and arranged for operation substantially as and for the purpose set forth.

ALCIBIADES J. WHITTIER.
